UNITED STATES PATENT OFFICE.

WILLIAM WALTON BROWN AND LEWIS ADELBERT GATES, OF SAN FRANCISCO, CALIFORNIA.

APPARATUS FOR EXTRACTING THE PRECIOUS METALS BY MEANS OF THE LEAD BATH.

SPECIFICATION forming part of Letters Patent No. 289,064, dated November 27, 1883.

Application filed April 19, 1883. (No model.)

To all whom it may concern:

Be it known that we, WILLIAM WALTON BROWN and LEWIS ADELBERT GATES, citizens of the United States, residing in San Francisco, county of San Francisco, State of California, have made and invented certain new and useful Improvements in Apparatus for Extracting the Precious Metals by Means of the Lead Bath; and we do hereby declare that the following is a full, clear, and exact description of the same, the accompanying drawings being referred to as a part of this specification.

Our invention relates to certain improvements in extracting gold and silver from their ores by what is generally known as the "lead-bath" process, and will be understood as hereinafter set forth and claimed.

The following description fully explains the manner in which we proceed to construct, apply, use, and operate our said invention, Figure 1 of the drawings referred to being a side view of an apparatus set up ready for operation, and showing an inclined ore-heating cylinder in elevation, its furnace and chimney in section, and the lead-bath vessel and furnace partly in section to expose the mechanism for introducing the ore into the lead. Fig. 2 is a plan of Fig. 1, the furnace and chimney of the heating-cylinder being in horizontal section. Figs. 3, 4, and 5 are views in detail and on a large scale of the lead-bath vessel, the ore-carrier, and its scraper, Fig. 3 being a vertical section through the vessel, the ore-chute, its feeding device, and the hood and apron, and vent for gases, by which the air is excluded from the ore; and Figs. 4 and 5 are respectively a plan and cross-section of the carrier.

We will proceed first to describe the construction and application of the mechanism by which we convey the ore through the molten lead and discharge it into the lowest portion of the bath, and afterward explain and show the connection and combination of the other parts necessary to produce a complete apparatus.

The vessel A is a cylindrical pot with a spherical or rounding bottom, of any suitable size to contain a body of lead. It is set within a furnace, A', over a grate-surface, a, by means of which the lead is kept in a molten condition during the operation. Upon the top or

rim of the furnace, at one side of the pot, a forked or double bracket, B, having shaft-bearings b in line, but inclined at an angle of about forty-five degrees out of the horizontal, to receive and support an inclined shaft, C, the true bearings being at such distance apart as will give required support to the shaft. The shaft C is set at this angle, and projects above the brackets, where a pulley, d, is fixed on it, and extends downward into the pot below the point where the level of molten lead will be kept. In the lower end of the shaft C is fixed an open center-wheel, D, having a rim, D', that is rectangular in cross-section, and arms 65 or spokes D', that join rim and hub D' together. This wheel being set square on its shaft, it extends diagonally through the bath from the top surface down to a point at or near the lowest part of the pot. The diameter of the 70 wheel is then determined by the size of the pot. The upper face of the rim D' is formed, somewhat after the manner of a cog-wheel, with alternate teeth, cogs, or projections and spaces or depressions, in regular manner, all 75 round. The upper part and a portion of one side of the rim are covered by an annular shield, E, which fits over the face and extends downward, both on the inside and the outside of the rim. This annular cover or casing is stationary, and the discharge end or mouth of the ore-conductor leads into it at the highest point, and directly over the cavities or pockets in the face of the rim. The object of this casing is to prevent the ore from being thrown off or 80 discharged from the pockets until they reach the lowest portion of the bath. One end of the casing is therefore carried down to this point, so that nearly the entire half of the rim of the carrier is incased on one side, but on 85 the opposite half or upward moving of the carrier the rim is uncovered, except in the vicinity of the feed.

A chute or connection, F, terminates in a vertical spout, F', rectangular in cross-section, 90 having a small corrugated roller, g, set in the mouth to regulate the discharge of the ore into the carrier, and which rotates as the carrier revolves, and to be driven by frictional contact with the rim of the wheel D'. This roller 100 fills the space between the walls of the spout F', and it is corrugated or formed with cavi-

ties or pockets. Rotation of this roller being always in proportion to the motion of the wheel D, the discharge of the ore into the rim-cavities is controlled and determined by the velocity of the wheel. A horizontal flange or holding-plate, h, is bolted to the rim of the pot, and supports the wheel-casing and also the vertical spout, it being formed in one piece with these parts, or the parts are firmly fixed to its outer overhanging edge.

I is a semi-cylindrical cap or hood entirely surrounding and inclosing the spout, so as to exclude the outer air from the discharging ore. The rear and sides of the hood rest upon the rim of the pot, while the front edge and that portion of the side beyond the rim is carried down to the surface of the lead. These over parts inclose the upper portion of the wheel and casing, and as long as the level of the molten lead is maintained above the edge of the hood perfect exclusion of the air is obtained. It should be understood, of course, that the joints between the edge of the hood and the pot and spout fit closely, or are properly closed to prevent leakage of air into the hood.

J is a vent-tube running down through the hood I into the top of the casing, for the purpose of allowing gases to pass off.

In connection with the ore-carrier D we employ an automatic scraper to remove the ore from the wheel-pockets as soon as they reach in turn the lowest part of the bath. This device is an arm, K, placed at the front of the pot in position to extend into the lead bath immediately over that portion of the wheel-rim which runs deepest into the lead. Its lower end terminates in a flat blade or scraping-edge, and an alternate rising and falling motion is given to the arm, by which the scraping-edge passes regularly over the projections and into the depressions, thus following and bearing against the surface of the rim. This movement and action are produced by the mechanism shown in Fig. 3. A hub or collar, K', free to slide upon the shaft, carries a curved arm or bracket-piece, K², the curved end of which has a friction-roller on a stud, m. Upon this shaft C, between the arms of the bracket B, is a cam, N, with a circumferential groove in its face, the form of which conforms to the form of the face of the wheel-rim. The stub of the hub-arm K² is brought in line and working position with respect to this groove, so that rotation of the cam shall produce a regular rising-and-falling motion of the arm K and move the scraper the required distance up and down to keep it in contact with the irregular surface of the revolving wheel or carrier. The cam-groove will have as many elevations and depressions as are contained in the wheel; or either a groove-cam or an edge-cam can be used. In the latter case the cam would only produce the lifting movement of the scraper, and a spring would be required to depress the arm after each lift.

Any suitable mechanism for moving the scraper-arm up and down can be used instead of the cam, as we do not limit ourselves to any particular way of making the scraper move over the cogs or irregularities of the wheel-rim. The movement of the hub K' is confined to a perpendicular one, or in line with the shaft, by means of a guide-pin, k³, on the top of the arm K, working through a hole in the flange of the lower arm of the bracket.

If the lower part of the wheel-casing requires additional support beyond what is derived from its attachment at the upper end to the rim of the pot or the feed-spout, a flange, R, may be carried from the rim of the pot at the side down into the bath and attached to the side of the casing at the lower part.

In the operation of the apparatus the ore is introduced to the wheel from the feed-spout, and, falling upon the rim, each cavity becomes filled with as much as will remain on it as the rim passes between the side and top of the stationary casing. These charges thus confined are carried downward through the bath, but within the casing, until they pass out from beneath the casing, where the cavities are relieved of the ore as they pass under the scraper. The ascending side of the wheel then passes upward and the cavities receive new charges as they pass in succession under the feed-spout. The ore to be treated is first brought to its required heated condition in a suitable furnace, from whence it is conducted through flues, chutes, or passages to the feed-spout. To properly and successfully carry on the process, the pot should be located in close proximity to the furnace, so that the heated ore can be taken directly from its discharge and without exposure into the feed-spout, and thence to the carrier. An arrangement of such complete apparatus is illustrated in Fig. 1 of the drawings, where an inclined revolving ore-furnace, with stationary fire-box and flue-chamber, is required to bring the ore to the required temperature. The ore-cylinder X is supported upon and driven by gear-wheels, and its tubular ends are inserted in apertures in the inside wall of stationary chambers Y and Y', the front one having the discharge flue and chute f and the necessary fire-box y, while the rear one, Y', is the chimney-flue. The ore is introduced in the upper tubular end of the cylinder through a hopper and spout, Z, and the movements of the fire and gases and the progression of the ore take place in contrary directions. All these features are common to any revolving roasting-furnace, however. We therefore do not claim any special novelty in this part of the apparatus, but only the construction of an ore-heating apparatus with our lead-bath apparatus to deliver the ore in a heated condition without exposing it to the air.

It will be noticed that the carrier D, in addition to its function as a carrier to convey the ore down into the lowest part of the bath,

operates upon the molten lead during the process to keep it continually stirred up or in a state of agitation, thereby producing a current that assists the metal in driving off the worthless particles and bringing such matter to the surface.

Having thus fully described our invention, what we claim, and desire to secure by Letters Patent, is—

- 10 1. In an apparatus for treating ores by the lead-bath process, an ore-carrier for receiving the ore from the delivery-spout and conveying it into the bath, said carrier consisting of a revolving wheel having depressions, corrugations, cavities, or pockets for containing the ore formed in the rim thereof, said wheel being set at an inclination from the perpendicular line, substantially as shown, and for the purpose set forth.
- 20 2. The combination of a suitable pot or vessel to contain a bath of metal and maintain it in a molten condition, revolving mechanical ore-carrier D, vibrating scraper K, stationary casing E, vent-tube J, feed-spout F', hood I, and mechanism for imparting to said ore-carrier a rotary motion, substantially as hereinbefore described.
- 30 3. The combination, with the inclined revolving ore-carrier, having brackets, pockets, or ore-cavities, of the stationary casing and vent-tube J, substantially as hereinbefore described.
- 40 4. The combination, with the pot or vessel, of the ore-spout F' and hood I, having the de-

pending apron or front portion adapted to 35 project into the surface of the molten metal, substantially as described, for the purpose set forth.

5. The combination, with the inclined revolving carrier D, having brackets, pockets, 40 or ore-cavities, of the casing E, vent-tube J, hood I, feed-spout F', and feed-roller, substantially as hereinbefore described, to operate as set forth.

6. The combination, with the inclined revolving carrier D, having brackets, pockets, 45 or ore-cavities in the rim, of the scraper K, actuating-arm K², and cam N, substantially as hereinbefore described, to operate as set forth.

7. The combination together of an ore-heating furnace, a close ore chute or conductor leading therefrom and adapted to deliver the heated ore into a closed feed-spout, out of contact with the outside air, a lead-bath pot or vessel to contain a body of metal in a molten 50 state, the inclined revolving ore-carrier, a mechanical scraper to operate upon the lower part of the carrier, the stationary casing, protecting-hood, feed-spout, and feed-roller, and mechanism for rotating said carrier, all substantially as hereinbefore described, to operate as set forth.
